UNITED STATES PATENT OFFICE.

JAMES B. DAVIE, OF BROOKLYN, NEW YORK.

PIPE-MOLDING MACHINE.

1,208,107.

Specification of Letters Patent. Patented Dec. 12, 1916.

Application filed February 24, 1916. Serial No. 80,105.

To all whom it may concern:

Be it known that I, JAMES B. DAVIE, a citizen of the United States, and a resident of the borough of Brooklyn, county of Kings, 5 city and State of New York, have invented certain new and useful Improvements in Pipe-Molding Machines, of which the following is a specification.

My invention relates to the formation of 10 pipe molds and refers particularly to a device whereby a sand mold may be made rapidly, economically and effectively.

One object of my invention is a device 15 whereby a sand mold suitable for pipes may be formed, packed, smoothed and black-washed mechanically.

Another object of my invention is a device 20 whereby the sand may be packed uniformly and evenly.

Another object of my invention is a device 25 whereby the rapidity of the production of a pipe mold may be greatly increased over the present known methods.

Another object of my invention is a device 30 whereby the rotary and longitudinal movement of a pattern through the flask will form and compact a sand mold.

Another object of my invention is a device 35 in which the passage of a plug through the formed sand mold will thoroughly black-wash the mold.

Other objects of my invention will become 40 evident upon a consideration of my specification and claims.

In the device of my invention, I overcome 45 the many objections to the present employed methods of making sand pipe molds with their incident slowness of production, high cost of labor employed, and uncertainty of 50 results due to hand labor, by employing a pattern which is caused to pass through the flask with a revolving motion, that will pack the sand evenly and thoroughly to any desired thickness, with a maximum of production and a minimum of labor, the same device being suitable for the further black-washing of the mold.

One form of my device, which will indicate 55 the scope and idea of my invention, is shown in the accompanying drawings, in which like parts are indicated by similar numerals.

Figure 1 is an elevation, partly in section, showing a battery of two devices. Fig. 2 is a cross section through the line 2—2 of 55 Fig. 1. Fig. 3 is an enlarged cross-section of the pattern and its moving parts. Fig. 4 is an enlarged view of the distributing blades of the pattern. Fig. 5 is a cross-section through the line 5—5 of Fig. 4. 60

An ordinary flanged pipe mold flask 6 is removably attached to the tubular pattern container 7 by means of the clamps 8, situated at convenient places. The container 7 is removably attached to the gear containing chamber 9, by means of the bolts 10, 10. The gear containing chamber 9 is attached to the floor or support 11, by means of the bolts 12, 12, in alinement with the piston containing chamber or pit 13. 70

Within the pattern containing chamber 7, is situated a pattern 14, fitting closely within the sides of said chamber 7, but capable of movement therein. The diameter of the flask 6 is greater than the diameter of the pattern 14. The upper portion of the pattern 14 is formed into the shape of a truncated cone 15, adjacent to which and attached thereto are a number of outwardly projecting distributing blades or 80 guides 16, 16 having parallel curved outer edges. These blades 16, 16 extend upwardly from the recess 54 within the upper portion of the pattern 14, the outer edges thereof being in a plane parallel to the surface of 85 the truncated cone 15, and being integral or attached to the angular ring 55 attached to the top of the truncated cone 15; the outer edge of the blades 16, 16 being flush with the outer edge of the ring 55, the diameter of 90 the ring 55 being less than the diameter of the pattern 14. This formation of the pattern and the blades allows the sand to pass downwardly between the surface of the truncated cone 15 and the inner surface of 95 the flask 7, the shape of the blades being such that the revolution and upward motion of the pattern, as described later, will cause the sand to be conveyed and compressed with great regularity and uniform density 100 into the space between the flask 7 and the pattern 14. Within a recess 17 within the upper coned top of the pattern 14, is the end of a rod 18 extending upwardly, the

100

lower end of the rod 18 being supported by means of a disk 19, rotatable upon the ball bearings 20. Situated above the supporting means is cone 21, extending from the 5 rod 18 downwardly to the circular edge of the top of the truncated cone 15 to prevent the sand from finding its way into the bearings and supporting members at the top of the pattern. The upper end of the rod 18 10 is connected with a flexible rope or chain 22, for purposes to be described later. The cone 21 is attached to the pattern 14 by means of the set bolts 62.

A square shaft 23 is attached at its upper 15 end to the support 24, which in turn is attached to the pattern 14 at the top of the recess 25 in the lower end of the pattern 14. The shaft 23 is attached to the support 24 by means of a bayonet joint 26, so that a 20 half turn of the pattern 14 will release it from the shaft 23. The shaft 23 passes downwardly through the revolute sleeve 27, having a square bore to fit the square shaft, the sleeve 27 being revolute within the 25 bearing 28. The square shaft 23 then passes downwardly through the square cored gear wheel 29, which meshes with the gear wheel 30, the gear wheel 29 being revolute upon the bearing 31. The end of the shaft 30 23 is revolutely attached to the piston 32, by means of the ball bearings 33, the piston 32 working within the piston chamber 13. A support 35 prevents the piston from 35 reaching the bottom of the piston chamber, and ball bearings 36 allow the revolution of the piston 32 when it rests upon the support 35. A pipe 37, situated below the top of the support 35, connects the piston chamber 13 with the air, the pipe terminating 40 in a valve 38.

The gear wheel 30 is fixedly attached to the shaft 39, which in turn is connected to a source of revolution, as the motor 40.

The rope 22 is capable of being passed 45 over the sheave 41 and around the drum 42, by means of the motor 43, these elements being supported upon the revolute support 44.

A sand chute 45, allows the introduction 50 of sand into the flask 6 from the sand hopper 46, into which sand is supplied by any convenient means.

The black-wash plug 47 is cylindrical in 55 form, of slightly less diameter than the pattern 14, and has affixed to its upper end, a flexible washer 48, as of rubber, the diameter of which is equal to, or slightly greater than, the diameter of the pattern 14. Within a recess within the lower side 60 of the plug 47, is a bayonet joint 49, whereby the rod 18 may be quickly and effectively attached or detached.

A black-wash outlet pipe 50 is so situated 65 that it is below the top of the pattern 14, when the pattern is at its lowest possible

position and flush with the top of the black-wash plug when it is at its lowest position. This pipe 50 connects with the reservoir 51.

It is preferable to arrange the flasks and mechanism in pairs, around the support 44, 70 as shown in Fig. 1, so that the operation may be practically continuous.

The operation of the device is as follows: The pattern 14 affixed to the square shaft 23 by means of the bayonet joint 26 is at 75 its lowest position, that is until it rests upon the floor 61 of the chamber 7. The cock 38 is opened to allow access of air through the pipe 37 below the piston 32. The gear wheel 29, is revolved by means of 80 the gear wheel 30, the shaft 39 and the motor 40. The revolution of the gear wheel 29 causes the square shaft 23 to revolve and also the pattern 14 to which it is attached, the revolution of the shaft 23, however, not 85 causing the revolution of the piston 32, on account of the ball bearings 33. When the pattern 14 is revolving, sand 53 is introduced into the flask 6 by means of the chute 45. When sufficient sand has been introduced, which may be about sufficient to 90 cover the cone 21, the pattern 14 is raised through the flask 6, by means of the motor 43 and the rope 22, the flow of sand being continued. The pattern 14 is thus given 95 both an ascending and rotating movement, during which the sand is packed and distributed evenly and thoroughly between the outer surface of the pattern 14 and the inner surface of the flask 6, the former having a tendency to pack the sand and smooth the inner surface thereof. When the pattern 14 has reached the top of the flask 6, the socket mold may be formed in the usual manner and then the pattern 14 is removed 100 from the flask 6 by a further upward movement of the rope 22 and the motor 40 stopped. The upward movement of the pattern 14 and the piston 32 draws air into 105 the piston chamber 13 below the piston 32 through the pipe 37, the valve 38 being open. The air valve 38 is then closed, and the pattern 14 removed from the square rod 23 by means of the bayonet joint 26, and while suspended is revolved over and lowered into a second flask, which has been 110 placed in position, thus allowing of continued action. The air beneath the piston 32 retains the latter in its raised position and also the square rod 23 attached thereto. 115 A black-wash plug 47 is then attached to the top of the square rod 23 by means of the bayonet joint 49, and a sufficient quantity of black-wash liquor poured thereon. The air cock 38 is then opened sufficiently 120 to allow the proper lowering of the piston 32 and the black-wash plug, the black-wash being thus thoroughly and evenly applied to all parts of the sand mold 52. When the plug 47 has reached its lowest position, the 125 130

excess of black-wash liquor remaining thereon escapes through the pipe 50 into the reservoir 51. The flask 6 and the inclosed pipe mold 52 are then removed and 5 baked in the usual manner, the black-wash plug removed, and a new flask introduced for the next mold.

It is thus seen that the formation and preparation of the sand mold are accomplished by the upward revolving motion of 10 the pattern and the downward motion of the black-wash plug. It is to be further noted that the black-washing operation requires no power, as the plug descends by 15 gravity controlled by the air cushion beneath the piston to which the plug is attached. It is evident that these operations can be accomplished with great regularity 20 and rapidity and at a minimum of labor cost.

It is evident that all of the parts described in detail in the description of the drawings may be varied, without interfering with the practical operation or construction 25 of the device of my invention, and therefore I do not limit myself to the particular size, shape, number or arrangement of parts as described, all of which may be varied without going beyond the scope of 30 my invention as described and claimed.

What is claimed, is:

1. In a device of the character described, in combination, a cylindrical flask, a piston, a piston box, a piston rod, a cylindrical pattern 35 of less diameter than the flask removably attached to the downwardly extending piston rod attached to the piston, said piston being movably incased within the piston box, sand distributing blades upon the pattern, and means for moving the pattern through the flask with a revolving motion.

2. In a device of the character described, in combination, a cylindrical flask, a piston, a piston box, a piston rod, a cylindrical pattern 45 of less diameter than the flask removably attached to the downwardly extending piston rod attached to the piston, said piston being movably incased within the piston box, means for moving the pattern through the 50 flask with a revolving motion, a black-wash plug, means for removably attaching the black-wash plug to the piston rod, means for passing the black-wash plug through the flask, and means for depositing sand between the flask and the pattern.

3. In a device of the character described, in combination, a cylindrical flask, a piston, a piston rod, a piston box, a cylindrical pattern 60 of less diameter than the flask removably attached to the downwardly extending piston rod attached to the piston, said piston being movably incased within the piston box, means for moving the pattern through the flask with a revolving motion, means for admitting air beneath the piston during its 65

upward stroke, means for allowing and preventing the escape of said air from beneath the piston, and means for depositing sand between the flask and the pattern during the movement of the latter.

4. In a device of the character described, in combination, a cylindrical flask, a cylindrical pattern of less diameter than the flask and within the flask, sand distributing blades upon the pattern, a piston box, a piston, a 70 piston rod connecting the pattern with the piston, the piston being movable within the piston-box, means for raising and lowering the piston rod and pattern, means for rotating the piston rod and pattern during their 75 passage through the flask, and means carried by the pattern for the uniform distribution of sand between the pattern and the flask.

5. In a device of the character described, in combination, a cylindrical flask, a cylindrical pattern of less diameter than the flask and within the flask, a piston, a piston box, a piston rod connecting the pattern with the piston, the piston being movable within the piston-box, means for raising and lowering 80 the piston rod and pattern, means for rotating the piston rod and pattern during their passage through the flask, means for admitting and retaining air beneath the piston, means for removing the pattern from the 85 rod, and means carried by the pattern for uniformly distributing sand between the pattern and the flask during the movement of the former.

6. In a device of the character described, in combination, a cylindrical flask, a cylindrical pattern within the flask, said pattern being of less diameter than the flask, having an upper portion in the form of a truncated cylindrical cone and terminating in a cylindrical cone, sand distributing blades upon the pattern, a piston, a rod removably connecting the lower portion of the pattern with the piston, a piston-box containing the piston, gear wheels for revolving the rod and pattern, means for revolving the gear wheels, means for hoisting the pattern and rod through the flask, means for allowing the revolution of the piston during its passage through the flask, means for admitting, 100 retaining and allowing of the escape of air within the piston-box below the piston, and means carried by the pattern above the cylindrical portion thereof to distribute sand between the pattern and flask during the movement of the former.

7. In a device of the character described, in combination, a cylindrical flask, a cylindrical pattern of less diameter than the flask within the flask, sand distributing 105 blades upon the pattern, a ring surrounding the blades and flush with the true edge of said blades, a piston, a piston rod connecting the pattern with the piston, a piston-box containing the piston, means for moving the 110

pattern through the flask, means for revolving the pattern during its passage through the flask, means for disconnecting the rod and the pattern, means for allowing the pattern to revolve upon the means employed in passing it through the flask, means for allowing the piston rod to revolve without the revolution of the piston, a black-wash plug, means for attaching and detaching the black-wash plug to the piston rod, means for admitting air to the piston-box beneath the piston during the upward move-

ment of the piston, means for retaining the air beneath the piston, and means for allowing the exhaustion of the air from beneath 15 the piston allowing the piston to descend.

Signed at New York city, in the county of New York and State of New York, this 17th day of February, 1916.
